EXPANDER FOR CRACKING HYDROCARBON OILS

Ernest W. Zublin, Fort Worth, Tex., assignor to
 Texas Pacific Coal & Oil Co., Fort Worth, Tex.,
 a corporation of Texas

Application September 19, 1933, Serial No. 690,036

2 Claims. (Cl. 196—106)

This invention relates to an apparatus for cracking hydrocarbon oils in vapor phase and more specifically to a multiplicity of expander units having a novel arrangement of connecting 5 conduits for the passage of vapors being converted, and also of flues for the combustion or other gases employed in heating the units.

In a co-pending application Serial No. 656,206, filed February 11, 1933, by the present applicant 10 and others, a process of converting higher boiling hydrocarbons into lower boiling hydrocarbons is described which includes introducing cracking stock into contact with hot cracked vapors produced in the process whereby said vapors are 15 quenched and substantially vaporized, fractionating the resulting mixed vapors to produce a gasoline fraction as overhead and cracking distillate, condensing the gasoline fraction, vaporizing said cracking distillate, superheating said vapors to 20 a point between the flash evaporation and cracking temperature, and passing said vapors through a vertical expansion zone heated uniformly to a conversion temperature by means of a plurality of heat zones extending vertically therethrough, whereby the hot cracked vapors to be treated in 25 the beforementioned manner are produced. The apparatus of the present invention is designed particularly for use in processes of this type, although its utility is not limited thereto.

An object of the present invention is to increase 30 the flexibility and raise the efficiency of processes of the above type.

A further object is to provide a cracking apparatus capable of adjustment to control cracking 35 temperatures thereby to control the rate of cracking, at several stages of the cracking operation independently of other stages.

A more specific object is to provide a series of 40 interchangeable expander units, any one of which may be cut out of the process without interrupting the cracking operation thereby increasing the operating cycle of the apparatus.

A further object is to provide an apparatus 45 capable of being regulated by simple and quick adjustment to alter the time period of cracking without changing the rate of passage, of the vapors through the cracking apparatus, thereby permitting the apparatus to continuously operate at full capacity.

The construction of the expander units per se 50 forms no part of the present invention, although by far the best results are obtained by use of units of the design hereinafter described, the 55 details of the construction being described more

fully in a co-pending application Serial No. 662,676, filed March 25, 1933.

In its broadest aspects the instant invention 5 contemplates the arrangement of a multiplicity of three or more expander units connected by valved conduits in such manner that hydrocarbon vapors to be cracked and during cracking may be passed in series through any number or any combination of expander units and by-passed around any remaining units, each expander unit 10 being adapted for heating independently of the other units, thereby permitting optimum temperatures to be obtained in each unit, certain of the units to be heated while others remain unheated. With this arrangement any unit in 15 use can be cut out of operation for cleaning or other purpose and any idle unit put into operation by closing or opening valves in the by-pass and connecting conduits.

The apparatus of the present invention can be 20 better understood from the accompanying drawing in which;

Figure 1 diagrammatically represents a front elevation with parts in section,

Figure 2 represents an end view of an expander 25 unit, and

Figure 3 is a graphic view illustrating the adaptability or flexibility of the present apparatus in obtaining optimum temperature and time conditions in the cracking process, as will be 30 hereinafter explained.

The value of the apparatus of the invention 35 can be understood better from a consideration of the nature of the processes which are to be carried out in the apparatus and the theory upon which the operating conditions are based, said conditions being controlled by manipulation of the valves and dampers provided in the apparatus.

When the present apparatus is in use, hydrocarbon vapors of a cracking stock, superheated or 40 not as desired, are passed through the expander units in series at a predetermined rate, the temperature to which the vapors are heated in each expander being also predetermined to obtain the largest yield of desired cracked products. As is 45 well recognized in the petroleum industry, the largest yield from any certain cracking stock is obtained by regulating the operating conditions to obtain an optimum time and temperature product. (Each different cracking stock requires 50 different time and temperature conditions.) Many apparatuses have been designed to take advantage of this knowledge in a general way, but as far as the applicant is aware none has been 55 capable of regulation of the temperature of the

hydrocarbon vapors independently at several points such that optimum cracking conditions can be had during the whole period during which the vapors are being cracked, as is accomplished with the present apparatus.

The provision for independently regulating the temperature of the vapors at a plurality of points not only permits optimum temperature for a particular cracking stock but also permits the conditions to be adjusted to obtain maximum yields from any one of a variety of cracking stocks, including topped crude, gas oil and kerosene. The provision for putting into operation any number of expander units permits the time factor to be adjusted in correlation with the temperatures employed.

To illustrate the extreme flexibility of the present apparatus to obtain optimum time and temperature conditions, the operating data of the present apparatus as applied to three different runs has been shown in the graph, constituting Figure 3, of the drawing. With reference to this figure, the temperatures during the period of the cracking operations, as ordinates, have been plotted against the time factors, as abscissæ, the time being represented by the number of expanders instead of in seconds which evaluation is permissible because of the operation of the process at a constant throughput and of the fact that the size of the expanders for an existing apparatus is a constant.

The curves 1, 2, and 3 represent three different rates of heating, the initial and final temperature being the same in each case. The rate of cracking during the processes as represented by these curves differs to a very great extent as is evident from the generally accepted axiom that the rate of cracking approximately doubles for every twenty to twenty-five degrees F. increase in temperature between 750° and 1000° F. For example, the rate of cracking of the vapors in the heating curves 1 and 3, after passage through two expanders is about 16 or more times as fast in the latter than in the former curve, for there is a difference of 100° temperature.

It is obvious from these curves that the amount of cracking effected may be great, medium or small, dependent upon the temperatures employed during the whole of the cracking period. It is further obvious that the ability to regulate the temperatures of the series of expander units permits the apparatus to be used for cracking a wide variety of cracking stocks each under its own particular optimum temperature conditions, the optimum time being obtained by merely varying the number of expanders connected in the series.

A second set of curves can be derived from the present curves which represent the rate of cracking during the passage through the expander system. By integrating this new set of curves, the amount of cracking which has taken place at any point in the system can be easily estimated. From such calculations, it appears obvious that the amount of cracking can be greatly varied by altering the rate of heating or temperatures of the vapors at various points during the cracking period. The extreme flexibility of the cracking process obtained by the use of the instant apparatus is readily apparent.

With reference to Figures 1 and 2 of the drawing, there is illustrated a series of vertically elongated expander units 1 to 6 inclusive, pierced by a plurality of heating tubes 10 equi-distantly spaced from each other. Each expander unit is sur-

5 by a casing 11 of a sufficiently larger diameter than the expander unit to permit a portion of the heating gases to pass around the exterior of the expander, the provision for heating both interiorly and exteriorly, accomplishing uniform heating and cracking of the whole stream of vapors passing therethrough. The temperatures throughout the expander at any horizontal plane are substantially the same.

A furnace 12 is provided for supplying combustion gases for heating the expander units, the same being connected through a duct or flue 13 having valved openings 14 leading to each expander unit. The provision of valves permits the heating and the temperatures in each expander to be controlled independently. Though separate furnaces could be employed for each expander with some degree of satisfaction, better results are obtained by the use of a single furnace, for with this arrangement exchangeability between the expanders can be had without delay for temperature regulation of independent furnaces which in such case would be necessary.

Each expander unit is provided with a top 15 bolted or otherwise removably attached to the 25 casing walls 11. At the back of each casing there is a heating gas outlet conduit 16 leading to a manifold conduit 17, the conduits 16 being provided with valves 18. The conduit 17 leads to a heat exchange chamber 19 and finally to the 30 stack 20. Whereas, the illustrated furnace and flue arrangement is adapted for heating by upward passage of vapors through and around the expander units it should be understood that an arrangement adapted for downward passage is 35 also suitable and within the scope of the present invention.

Each expander unit has an inlet conduit 22 extending almost to its bottom, and an outlet conduit 23 terminating at its top. All of these 40 conduits connect into a manifold conduit 24. Valves 25, 26 and 27 are provided in said conduits as illustrated thereby enabling the cutting out of operation of any one or more expanders. The portions of the manifold conduit between the 45 junctions of the inlet and outlet conduits thereto serve as by-passes upon manipulation of the valves in obvious manner.

A heat exchange coil 30 is mounted in the chamber 19 and is preferably employed for superheating the vapors before their introduction into the cracking units. Alternatively the coil may be used for vaporizing the oil. As illustrated, the coil 30 is connected through valved lines 31 and 32 to the manifold conduit 24 leading to 50 the expander units. Additional heating units (not shown) may be provided between the lines 31 and 24 if necessary to bring the vapors to the proper temperature before introduction into the 55 expander units.

60 A valved steam inlet conduit 35 is connected to each inlet conduit 22, and valved outlet conduits or vents 36 to each outlet conduit 23. Steam is passed through any expander unit after it has been cut out of operation for cleaning, repairing 65 or for any other purpose.

The advantages obtained by the arrangement of the apparatus constituting the present invention may be summarized as follows:

70 1. The rate of flow of heating gases to each expander unit is controlled individually thereby permitting accurate and independent control within wide limits of the cracking temperature in each expander. 2. The number of units connected in series may be altered at any time thereby 75

permitting limitation or extension of the time period of cracking, the alteration being accomplished without changing the throughput of the cracking unit. 3. Any unit may be cut out of the process for cleaning or other purpose, and any idle unit substituted therefor without interrupting the process. 4. A series of small expander units can be built more cheaply than one or two large ones of the same total volume.

10 Whereas the present invention has been described with reference to expander units and a heating means of a particular nature, it should be understood that some of the advantages of the invention can be obtained while using units of 15 other and different construction. The field of the present invention is to be limited only by the scope of the claims appended hereto.

I claim:

1. An oil cracking apparatus comprising a multiplicity of expander units, casings enclosing said units, a manifold conduit for conducting vapors, inlet and outlet conduits connecting said manifold conduit and each of said expander units, valves in said manifold conduit and in said inlet 25 and outlet conduits adapted to cut out selectively

any of said units, a source of heating gases, a manifold flue connected to said source of heating gases and communicating with the interior of said casings for conducting heating gases thereto in indirect heat transfer relationship with respect to 5 said vapors, valve means controlling the admission of heating gases to said casings, and a discharge flue for said heating gases.

2. An oil cracking apparatus comprising a multiplicity of expander units, a manifold conduit 10 for conducting vapors, inlet and outlet conduits connecting said manifold conduit and each of said expander units, valves in said manifold conduit and in said inlet and outlet conduits adapted to cut out selectively any one of said units, a 15 source of heating gases, a casing enclosing each of said expander units, a manifold flue connected to said source of heating gases and leading to one end of each of said casings, a manifold discharge flue connected to the opposite end of each of said 20 casings and leading to a stack, and a heat exchange coil communicating with said manifold conduit and disposed in said discharge flue.
